The ornamental design for a utility cart with cookbook stand, as shown and described.

DESCRIPTION

FIG. 1 is a perspective view of the utility cart with cookbook stand with a cookbook shown in broken lines representing environmental matter being for illustrative purposes only and forming no part of the claimed design.

FIG. 2 is a front elevational view thereof.

FIG. 3 is a rear elevational view thereof.

FIG. 4 is a left side elevational view thereof.

FIG. 5 is a right side elevational view thereof.

FIG. 6 is a top plan view of the utility cart with cookbook stand; and,

FIG. 7 is a bottom plan view thereof.
